UNITED STATES PATENT OFFICE.

GENEARL J. BATES, OF BRYSON CITY, NORTH CAROLINA, ASSIGNEE OF ONE HALF TO
WALTER W. JENKINS, OF BRYSON CITY, NORTH CAROLINA.

RAILWAY TIE.

Application filed September 13, 1927. Serial No. 219,278.

This invention relates to railway ties and fasteners and aims to provide a novel form of metallic tie so constructed that it will possess the usual resilient qualities of the 5 wooden tie and will withstand strains and weather conditions which otherwise cause deterioration of the usual wooden tie.

An important object of the invention is to provide means whereby the rails supported by the tie will be held against spreading and creeping, to the end that a practical 10 and safe tie is provided.

A further object of the invention is the provision of a metallic tie in the form of a 15 rectangular shell, there being provided wooden sections inserted in the ends of the tie or shell on which the rails of the track are supported.

With the foregoing and other objects in view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawing:

30 Figure 1 is an elevational view illustrating a tie constructed in accordance with the present invention, one end of the tie being shown in section.

Figure 2 is a plan view of a tie, one of the 35 rails of the track supported by the tie being omitted.

Figure 3 is a sectional view taken on line 3—3 of Figure 2.

Figure 4 is a perspective view illustrating 40 one end of the tie, the wooden block being removed.

Figure 5 is a perspective view of the fastening plate.

Referring to the drawing in detail, the 45 tie includes a rectangular body portion indicated generally by the reference character 5, the same being formed of metal.

The tie is of the usual length, the same 50 being hollow to receive the wooden end sections 6 that are driven into the ends of the shell providing supports for the rails that are positioned on the tie. Transverse cut out portions 7 are formed at the ends of the shell or body portion, the cut out portions 55 extending downwardly below the upper edge

of the tie defining lateral shoulders and providing a space sufficiently wide to receive the base of a railway rail.

The upper surface of the tie is cut away at the ends thereof, the cut away portions 60 being indicated by the reference character 8 and as shown extend from the ends of the tie, and merge with the cut out portions formed transversely of the tie.

The cut out portions 8 define inwardly extended flanges 9, the spaces between the flanges being sufficiently wide to accommodate the fastening plates 10 which are provided with upstanding end portions 11 conforming to the shape of the side of a railway 70 rail so that a rail positioned on the tie will be firmly held by the fastening plates.

Spike openings 12 are provided in the plate and are designed to receive spikes so that the fastening plate may be securely held 75 in position. Openings 13 are formed in the body portion adjacent to the cut out portion 7 for the reception of spikes that are driven into the wooden end sections to secure the rail in position.

At one side of the rail which is indicated by the reference character 14 is a spike 15, the head thereof contacting with the rail to hold it in position. In order to permit the fastening plate to be held in close engagement with the wooden section and rail, a depression is formed on the under surface of the plate defining a clearance for the head of the spike over which the plate is positioned.

From the foregoing it will be obvious that due to this construction, a metallic tie is provided, the wooden sections lending resiliency to the tie, the metallic portion lending strength and durability.

I claim:

A railway tie including a rectangular metallic body portion, the upper side of the body portion being closed throughout substantially the entire length thereof, the upper side of the body portion being formed with transversely disposed cut out portions arranged adjacent to the ends thereof, the cut out portions being of widths to receive the base of a railway rail, the upper side of the body portion being provided with longitudinal cut out portions communicating with the first mentioned cut out portions and extending to the ends of the tie, the last mentioned cut out portions defining lateral 110

flanges, wooden blocks fitted in the ends of the tie and on which rails rest, spikes extending into the wooden blocks to secure the rails to the tie, and elongated fastening plates of 5 widths to fit between the flanges, and said plates having upstanding end portions fitted against the rail associated therewith, and

10 said plates having offset portions to accommodate the heads of spikes used for securing the rail in position.

In testimony that I claim the foregoing as my own, I have hereto affixed my signature.

GENEARL J. BATES.
